LOOSE-LEAF BINDER

George H. Dawson, Chicago, and Paul O. Unger,
Elmhurst, Ill., assignors to Wilson-Jones Com-
pany, Chicago, Ill., a corporation of Massachu-
sets

Application September 2, 1943, Serial No. 500,878

3 Claims. (Cl. 129—24)

1

This invention relates to a ring binder and more particularly to the means for securing the ring sections to wooden ribs.

It is an object of this invention to provide a ring binder with wooden ribs and steel ring sections secured to said ribs in an inexpensive manner. Other objects of this invention will become apparent upon reading the following description, taken in conjunction with the accompanying drawings, in which:

Figure 1 is a fragmentary top elevation of a loose leaf binder embodying the invention with parts broken away to more clearly illustrate the structure;

Figure 2 is an end view showing the rings in closed position;

Figure 3 is a perspective view of one rib plate or toggle member;

Figure 4 is a perspective view of the ring carrying plate with ring section secured thereto being shown in dotted lines; and

Figure 5 is a fragmentary perspective view showing the ring carrying plate secured to the toggle plate.

In the drawings, the reference numeral 2 indicates a back member to which cover members 3 and 4 are hinged in any suitable manner. A cover plate 5 is secured to the back member by means of a plurality of rivets 6. The cover plate is countersunk as indicated at 7, and the back member is countersunk, as indicated at 8, to prevent the rivets from projecting beyond the top of the cover plate or the bottom of the back member.

A pair of wooden ribs or toggle plates 9 are arranged in side by side relationship in the cover member 5 with the downturned edges 10 and 11 of the cover plate embracing the outside longitudinal edges of the toggle plates. The toggle plates are strengthened by means of a longitudinal rib 12 which is integral with each toggle plate. The reinforcement rib 12 is disposed approximately centrally of the toggle plate 9. The toggle plate 9 is provided with a plurality of recesses 13 to provide clearance apertures for the rivets or eyelets 6.

The longitudinal edges of each toggle plate 9 are notched to provide recesses 14 and 15. A plurality of individual ring carrying plates 16 are secured to each toggle plate 9 by means of a finger 17 embracing one edge of the toggle plate 9 and a pair of fingers 18 embracing the opposite longitudinal edge of the toggle plate. The fingers 17 and 18 are disposed within the confines of the notches 14 and 15 so that none of them

2

project outside the planes of the longitudinal edges of the toggle plates 9. Ring sections 19 are secured in each ring carrying plate in any suitable manner.

5 Each ring carrying plate 16 is provided with a finger 20 which projects over the edge of the oppositely disposed toggle plate. The ring carrying plate is provided with a corner notch 21 to provide clearance for the projecting finger of the oppositely disposed prong carrying plate.

When the toggle plates 9 are arranged in side by side relationship with their outer longitudinal edges embraced by the edges 10 and 11 of the cover plate 5 and the ring sections are moved to

15 open position the cover plate restricts the movement of the toggle plates and maintains them in proper working relationship. When the ring sections 19 are moved from open to closed position,

20 the interlocking fingers 20 engage the edge of the oppositely disposed toggle plate in the spaces provided by the recesses 21 to prevent relative displacement of the inner edges of the toggle plates. The interlocking fingers maintain the side by side relationship between the toggle plates

25 during the entire motion from one position of the rings to the other. Each finger 20 acts as a stop member to prevent the inner edge of its toggle plate from slipping downwardly by its engagement with the opposite toggle plate, and prevents the inner edge of the opposite toggle plate from slipping upwardly by the same engagement.

Although we have described a preferred embodiment of our invention in detail, it will be understood that the description thereof is illustrative, rather than restrictive, as many details may be modified or changed without departing from the spirit or scope of our invention. Accordingly, we do not desire to be restricted to the exact construction described, except as limited by the appended claims.

We claim:

1. In a loose leaf binder, a pair of toggle plates, and a plurality of individual ring carrying plates each secured to one of said toggle plates, each of said ring carrying plates having a finger engaging said other toggle plate to restrain the downward vertical movement of said toggle plates.

2. In a loose leaf binder, a cover plate, a pair of non-metallic toggle plates arranged in side by side relationship in said cover plate, a plurality of metallic plates secured to each of said toggle plates, a ring section secured to each of said metallic plates, and an integral finger on each of said metallic plates, said fingers engaging said

toggle plates to restrain the downward vertical movement of said toggle plates.

3. In a loose leaf binder, a cover plate, a pair of non-metallic toggle plates arranged in side by side relationship in said cover plate, and a plurality of pairs of ring carrying plates secured to said toggle plates in transversely aligned rela-

tionship, said ring carrying plates each having an integral finger projecting over the toggle plate to which the opposed ring carrying plate is secured whereby said toggle plates are interlocked in said cover plate.

GEORGE H. DAWSON.
PAUL O. UNGER.
